UNITED STATES PATENT OFFICE.

FREDERICK C. STUART, OF JOLIET, ILLINOIS.

SPRING SWITCH AND OPERATING MEANS THEREFOR.

Application filed August 28, 1924. Serial No. 734,710.

My invention relates to an improvement in railway track switches of the split type in which the point or switch rails are connected to an operating stand by means of a 5 coil spring so designed as to normally hold the switch in closed position and to automatically return the switch points to their normal or closed position after a train has trailed through them.

10 The primary object of my invention is the provision of a spring switch having locking means associated therewith which lock the switch points after they have been opened by a pair of car wheels until after 15 the entire train has passed through the said switch and which thereupon release the said switch points and allow them to return to their normally closed positions, with suitable cushioning means to prevent the switch 20 points being thrown against the sides of the co-operating rails with such force that they are broken or damaged.

This type of switch is commonly used where a double track leads into a single 25 track, the switch being normally in closed position and is opened by trains running from double track onto the single track, the switch points being crowded over to the proper position by the flanges on the engine 30 and car wheels. After the train has passed through, the spring attached to the switch points automatically returns the switch to the position it occupied before the train passed through.

35 The principal difficulty with this type of switch is that immediately after the wheel runs off of the point, the switch is thrown back to its normal position and is operated again by the next set of wheels that passes 40 through it. This continuous operation of the switch by long trains wears out the switch points and connections with great rapidity and makes the switch accordingly expensive to maintain and keep in repair. The constant 45 vibration and wear of the switch frequently breaks bolts and connections so as to render the switch unsafe for use, especially with trains running against the points or from single track to double track.

50 Another and further object of my invention is the provision of automatic locking means for railway switches of the spring type in which the switch points are locked in closed position and retained in such position 55 by electrical locking means operated by a pair of car wheels running against the said

switch points and which also effectively lock the switch against tampering or prying open the switch points as it might be possible to accomplish with the ordinary type 60 of switch stands.

Another and further object of my invention is the provision of a spring switch which is durable in service, which is not easily broken or damaged in use and which 65 is simple and positive in its operation.

These and other objects of my invention will be more fully and better understood by reference to the accompanying drawings in which:

70 Figure 1 is a plan view of my improved invention;

Figure 2 is a top view of my improved locking device partially in section;

Figure 3 is a side view partially in section and partially in elevation of the locking 75 device shown in Figure 2;

Figure 4 is a longitudinal sectional view of the cushioning and locking device for the 80 switch;

Figure 5 is a cross-sectional view of the cushioning and locking cylinder on line 5—5 of Figure 4;

Figure 6 is a vertical sectional view of the valve adapted to partially control the 85 flow of liquid from one end of the cushioning and locking cylinder to the other;

Figure 7 is a modification of the connecting means from the locking device to the 90 switch points; and

Figure 8 is a wiring diagram showing the 95 electrical circuits leading to various operating parts of the apparatus.

Referring now specifically to the drawings, a track comprising a pair of rails 10 and 11 are shown (Figure 1) with a pair of other split rails 12 and 13 adapted to engage against the sides of the rails 10 and 11 in the usual manner. The rail 13 forms a continuation of one of the rails making up a main track section, and the rail 12 is one of the rails forming the beginning of a switch track section or cross-over leading from the main line, the rail 11 being curved in the usual manner to form the beginning of the other rail for the switch track section. The usual switch stand 14 is provided, having a connecting rod 15 leading therefrom and secured to a second rod 16 which extends through a loop 17 secured at each of its ends to a switch throw rod 18 which is connected at each of its ends to the rails 12 and 13.

A coil spring 19 is provided which is mounted inside of the loop 17 which normally exerts its force in the direction of the switch stand 14 so as to hold the switch 5 in normally closed position, but which allows the switch points 12 and 13 to move into open position when a car or locomotive passes therethrough and onto the rails 10 and 11. Secured to the rod 18 at its outer 10 end is a turn buckle 20 to which the piston rod 21 is secured, the said piston rod extending into locking and cushioning cylinder 22 which is mounted upon a plate 23 secured to the cross ties in any approved 15 manner. The cylinder 22 has a piston head 24 mounted thereon and has a plurality of ports 25, 25 therein which are normally closed by the valve 26 mounted upon the piston rod 21 and held against the side of 20 the piston head by a coil spring 27 which in turn is held in position by the stop 28 secured to the shaft 21 by means of a pin 29.

In the wall of the cylinder 22 and extending throughout a portion of its length is a 25 plurality of passages 30, 30, the said passages communicating with the interior of the cylinder and terminating a short distance from the rear end thereof so that when the piston head 24 is in its farthest rear position, 30 the edge of the piston head extends beyond the passages 30, 30. The cylinder 22 has openings in the side walls thereof at each 35 of its ends and within which nipples 31 and 32 are positioned in threaded engagement with the side wall of the cylinder 22, these nipples having elbows 33 and 34, respectively, to which short sections of pipe 35 and 36 are secured and to which a valve 37 is secured. The valve 37 is of the usual 40 check type and is controlled by a magnet 38 which is made up of an armature 39, a magnet core 40 and a magnet coil 41 with a non-magnet holding ring 42 positioned above the magnet coil 41 upon which the 45 armature 39 rests, the said magnetic core being supported upon a member 43 in threaded engagement with the said valve 37 to which the magnet core 40 is secured.

Secured to the armature 39 is a pin 44 50 having a closure member 45 at the lower end thereof and which is adapted to operate in connection with the valve seat 46 so that the bypass formed by the pipes and through 55 the valve leading from one end of the cylinder to the other is opened and closed as will be described more fully hereinafter.

A second connecting bar 47 is provided 60 which is connected to the rails 12 and 13 at the outer ends thereof and which has a second bar 48 secured thereto with a crank having a short arm 49 connected to the outer end of the arm 48 and the long arm 50, the 65 said crank being pivotally mounted by means of a pin 51 upon a plate 52 secured to a cross tie in any approved manner. A bar

or rod 53 is connected to the outer end of the long arm 50 of the crank and has a locking arm 54 secured thereto which leads into a locking casing 55. The said locking casing 55 has a normal locking dog 56 70 mounted upon a pin 57 with filler blocks 58 mounted on each side of the locking dog 56 and having at the opposite end of the casing 55 a reverse locking dog 59 mounted upon a pin 60 with filler block 61 on each side thereof, the said locking dogs being adapted to alternately engage in a notch 62 formed in the upper side of the bar 54. Positioned in the casing 55 is a normal locking magnet 63 which is secured to a 80 magnet supporting frame 64 in any approved manner. The said magnet 63 has a magnet coil 65 therein and a magnet armature 66 above said magnet 63 and a guide pin, 67 positioned therein and extending 85 downward through the magnet core 63 and resting upon the locking dog 56. The lower end of the pin has an enlarged portion 68 formed therein which acts as a stop to prevent the guide pin 67 from being pushed 90 upward to such a distance that the magnet armature 66 will not operate when the magnet is energized. A reverse locking magnet is provided which is made up of a magnet core 69, an armature 70, a magnet winding 95 71, an insulating ring 72 with a guide pin 73 having an enlarged portion 74 and which extends down into engagement with the locking dog 59 and which is adapted to engage in the notch 62 when the switch is in open position as will be more fully described hereinafter.

An alternative form of this connecting device is illustrated in Figure 7 wherein a rack bar 74 is shown which is connected directly to the bar 18 and engages a gear wheel 75 mounted upon any suitable foundation 76, the said gear wheel 75 engaging a larger gear 77 pivotally mounted upon a stud 78 and having an arm 79 extending upwardly therefrom to which a pulley rod 80 is secured and which in turn is secured to the locking bar 54 leading into the locking case 55.

Referring to Figure 8 wherein is shown a 115 wiring diagram illustrating the operation of the device, a plurality of main line track sections A and B are shown having a switch track comprising a pair of sections X and Y leading therefrom, each of the said sections of track being insulated from each other by sections of insulation I in the usual manner. The track section X has a pair of rails 81 and 82 with wires 83 and 84 leading therefrom to an electric battery 85. Connected to the rail 81 is a second wire 86, 125 which leads to a relay 87 with another wire 88 leading therefrom and which is connected to the rail 82 so that in normal operation of the device, a complete circuit is established through the wire 84, the rail 81, wire 86, 130

through the relay coil 87, wire 88, rail 82 and wire 83, back to the battery 85. The track section B is composed of a pair of rails 89 and 90 with the wires 91 and 92 leading therefrom to a battery 93. The rail 89 has a wire 94 leading therefrom to a relay coil 95, with a wire 96 leading from the relay coil 95 to the rail 90 so that a circuit from the battery 93 has established a normal 10 operation of the device through the relay coil 95. A battery 97 is provided having a connecting wire 98 leading therefrom to a switch 99 which in turn has a wire 100 leading therefrom and which is connected to a normal locking magnet 63. A wire 101 leads from the magnet 63 to a contact point 102 which is adapted to co-operate with the contact member 103 actuated by the relay 95 and shown in the drawing in open position, the circuit to the magnet 63 being completed through the contact members 116 and 108 with the wire 106.

A second wire 106 leads from the battery 97 to a relay member 108 which is adapted 25 to co-operate with the contact 109 having a wire 110 leading therefrom and which leads to the reverse locking magnet 69 with wire 111 leading therefrom which is connected to the wire 100 leading from the negative 30 side of the battery 97. Thus a circuit is established to the reverse locking magnet 69, the circuit to this magnet being established through the wire 111 which is connected to the lead wire 100 and the wire 110 through 35 the contact members 116 and 108. Connected to the wire 111 is a second wire 112 which leads to the magnet 38 which controls a valve mounted upon the cylinder 22 with a return wire 113 leading therefrom which in 40 turn is connected to the wire 110 leading to the reverse locking magnet 69. Secured to the wire 106 is a second wire 114 which leads to a contact point 115 in normal engagement with a relay member 116 and which in 45 normal operation of the device is held in the position shown in the drawing (Figure 8) so that all sections leading from the battery 97 to the various locking coils are disconnected.

In the operation of the device, when a car 50 wheel passes out over the track section X, a short circuit is established to the battery 85 which allows the relay members 116 and 108 to drop establishing a contact of member 108 with the member 109, thereby establishing 55 a circuit through the locking magnet 69 in the locking device 55 and also in the locking magnet 38 which operates the valve attached to the cylinder 22. As the wheels continue to pass outward on the rails, the 60 switch points 12 and 13 are pushed over until the switch is in open position and the locking bar 54 is moved longitudinally of the locking device 55 until the notch 62 is under locking dog 59 and as the electric current 65 is passing through the magnet 69 the

locking dog 59 will be forced downward into the notch 62 and held thus securely locking the switch in open position and holding it as long as the battery 85 is short circuited by the car wheels passing over the rails 81 and 82. The notch 62 is beveled at each of its sides to allow the locking dog to disengage itself from the locking bar as force is applied to the locking bar. The locking cylinder 22 is filled with oil and as shown in 70 the drawing is in reversed locking position of the cylinder. As the switch points 12 and 13 are pushed into open position of the switch, the piston head 24 travels backward in the cylinder and the oil therein flows 75 through the passages 30 in the wall of the cylinder and through the ports 25 to the front portion of the cylinder 22. As soon as the battery 85 is short circuited, the locking magnet 40 is energized by a circuit being 80 established through wires 112 and 113 and the closure member 45 is held in locked position by the magnet 40 so that the oil in the cylinder and bypass passages is prevented 85 from returning through the valve 37 to the front of the cylinder, also locking the cylinder in open position of the switch until the entire length of the train has passed out of the switch and the battery 85 is no longer 90 short circuited. Then the current is passing 95 through the relay coil 87 which, as long as this circuit is established, picks up the relay points 108 and 116, preventing contact between the members 108 and 109 so that the magnets 69 and 38 are de-energized 100 which allows the locking dog 59 to be thrown out of the notch 62 by the action of the coil spring 19 and allowing the switch to return to normal position. The action of 105 the cylinder is somewhat different because as long as the magnet 40 is de-energized, the valve member 45 and armature 39 is lifted by the pressure of the oil so that a slight amount of oil is forced from the front end of the cylinder through the bypass around 110 to the rear end and the piston head commences to travel toward the forward end of the cylinder. As soon as the rear end of the piston head reaches the beginning of the 115 passages 30, the oil travels through these passages very quickly to the rear end of the cylinder, but a sufficient time must elapse for the travel of the oil so that the switch points are prevented from being thrown over violently against the side of the rails and resulting in a breakage or damage to the switch points. In the case of a train proceeding in the opposite direction, that is, against the switch points 12 and 13, the battery 93 is short-circuited so that the relay coil 95 is de-energized and contact is established between the relay member 103 and the contact 102 which results in the magnet 63 120 and locking device being energized so that the bolt 67 is brought down upon the top 125 130

of the locking dog 56 which in this position of the switch is engaging the notch 62 and thus effectively locks the switch in closed position, as long as the battery 93 is short-circuited by the wheels passing over the rails 89 and 90.

While I have described more or less precisely the details of construction, I do not wish to be understood as limiting myself thereto, as I contemplate changes in form and the proportion of parts and the substitution of equivalents as circumstances may suggest or render expedient without departing from the spirit or scope of my invention.

15 What is claimed is:—

1. A locking device for spring switches comprising in combination, a combined locking and cushioning device attached thereto, an electrical apparatus adapted to automatically control said locking and cushioning device.

2. A spring switch control mechanism comprising in combination a cylinder, a by pass connecting each end of said cylinder, a valve controlling the passage of fluid through said by pass, electrical means for controlling the said valve, a piston in said cylinder, and operative connections between said piston and said switch.

30 3. A spring switch control mechanism comprising in combination a cylinder, a by pass connecting each end of said cylinder, a valve controlling the passage of fluid through said by pass, electrical means for controlling the said valve, a piston in said cylinder, operative connections between said piston and said switch, the said piston head having ports therein, and a spring controlled valve adapted to control the passage of a fluid through said ports.

40 4. A spring switch control mechanism comprising in combination a cylinder, a by pass connecting each end of said cylinder, a valve controlling the passage of fluid through said by pass, electrical means for controlling the said valve, a piston in said cylinder, operative connections between said piston and said switch, the said piston head having ports therein, a spring controlled

50 valve adapted to control the passage of a fluid through said ports, said cylinder having a plurality of passages in the walls thereof whereby fluid can flow from one end of the cylinder to another, the said passages being closed when a piston is at its 55 farthest point of travel at one end of the cylinder.

5. Spring switch control mechanism comprising in combination a cylinder, a piston head in said cylinder connected to the switch points, a by pass pipe around the said piston head, and electrical means operated by the passage of cars over the said switch points adapted to control the passage of fluid 60 through the said by pass pipe.

6. Spring switch control mechanism comprising in combination a cylinder, a piston located in said cylinder connected to the switch points, a by pass pipe around the said piston, a valve in said by pass, and electrical means controlled by the passage of cars over the switch points adapted to hold the said valve in closed position and allow the said valve to open after the cars have passed over the said switch points.

7. Spring switch control mechanism comprising in combination a cylinder, a by pass pipe connecting the ends of said cylinder, a valve located in the said by pass pipe, a magnet adapted to control the closing of the said valve and electrical connections to said valve adapted to retain the valve in closed position as car wheels pass over the switch points.

8. Spring switch control mechanism comprising in combination a cylinder having a fluid therein, a piston in said cylinder connected to said switch points, a by pass pipe connected to the said cylinder on each side of the said piston, a valve in said by pass pipe, electrical control means adapted to hold said valve in closed position when a train passes over said switch points and allow said valve to open after the train has passed over the said switch points.

Signed at Joliet, Illinois, this 21st day of August, 1924.

FREDERICK C. STUART.
